UNITED STATES PATENT OFFICE.

CHARLES T. FINKBEINER, OF WILKINSBURG, PENNSYLVANIA.

FAN.

No. 856,690.

Specification of Letters Patent.

Patented June 11, 1907.

Application filed April 2, 1906. Serial No. 309,442.

To all whom it may concern:

Be it known that I, CHARLES T. FINKBEINER, a citizen of the United States of America, residing at Wilkinsburg, in the county of Allegheny and State of Pennsylvania, have invented certain new and useful Improvements in Fans, of which the following is a specification, reference being had therein to the accompanying drawing.

10 This invention relates to certain new and useful improvements in fans, and the invention has for its primary object to combine a score card with a fan whereby the fan may be used for a double purpose by a spectator 15 of a game, such as base ball, and other games played in the warm season of the year.

My invention aims to provide a fan that can be used as an advertising medium, a score card being embodied in the fan, whereby 20 a spectator of a game, as base ball, may keep a record of the number of "runs" and "innings" of a game. In this connection, I have used a strong and durable construction, in connection with the fan, yet maintaining 25 an inexpensive article which can be readily used for advertising purposes.

With the above and other objects in view, which will more readily appear as the nature of the invention is better understood, the 30 same consists in the novel construction, combination and arrangement of parts to be hereinafter more fully described and claimed, and referring to the drawing accompanying this application, like numerals of reference designate corresponding parts throughout the several views, in which:—

Figure 1 is a front elevation of a fan constructed in accordance with my invention, Fig. 2 is a rear elevation of the same, Fig. 3 40 is a vertical sectional view of a portion of the fan illustrating one of the revoluble disks thereof, Fig. 4 is a front elevation of one of the disks, Fig. 5 is a vertical sectional view of a portion of the fan, Fig. 6 is a front elevation 45 of a ring or annulus used in connection with the fan, Fig. 7 is a front elevation of another form of disk used in connection with the fan.

To put my invention into practice, I construct my improved fan of a disk 1 of card 50 board, paste board or a similar inexpensive material. The disk upon its one side is ornamented either by the representation of a face or by a novel form of advertisement, the ornamenting and use to which the fan is put 55 being arbitrary. To the one edge of the disk is secured a conventional form of handle 2

preferably made of wood, the handle being riveted or otherwise secured to the disk as at 3.

In the present instance, I have illustrated the fan as representing the face of the "man in the moon," and in describing the location of the various disks used in connection with the fan, I will use the different parts of the face to designate the location of the various disks. The fan which I have illustrated is 65 particularly adapted as a score card for base ball games, and in connection with the fan, I use a small disk 4 containing the names 5 of the various base ball teams of a league, these teams representing the visiting teams, which 70 play upon the base ball grounds where the fan is used.

The disk 4 is revolvably mounted upon the rear side of the disk 1 by a rivet 6, said disk being located between the eyes of the face, 75 whereby one of the names carried by the disk 4 will be exposed through a slot 7 adjacent to the right eye of the face, figuratively speaking. The names upon the disk are arranged radially relative to the center of the disk, 80 whereby the disk can be revolved to expose either one of the names carried by said disk.

The right eye of the disk 1 is provided with two rectangular openings 8 and 9 and revolvably mounted upon the rear side of the disk 85 1 by a rivet 10, adjacent to the rectangular openings 8 and 9 is a ring or annulus 11 and a disk 12, said annulus and disk having consecutive numerals arranged thereon, from zero to nine. The disk is mounted within 90 the annulus 11 and retained therein by a strap 14 carried by said annulus. The numerals upon the annulus 11 and disk 12 are exposed through the openings 8 and 9, and are adapted to represent the number of 95 "runs" made by the visiting team.

Over the left eye, is printed the name of the home team, as "Pittsburg," and this eye is provided with two openings 15 and 16, in the rear of which is revolvably mounted an 100 annulus 17 and a disk 18, said annulus and said disk being constructed similar to the annulus 11 and the disk 12 heretofore described. The annulus and disk 17 and 18 are employed for keeping the record of the number of 105 "runs" made by the home team.

The annuli 11 and 17 and the disks 12 and 18, are provided with rearwardly extending knobs 19, whereby they may be easily and quickly rotated. It will of course be understood that the annuli are used for keeping the number of "runs" made by the teams, until 110

the "runs" exceed nine, at which time the disks are brought into use to maintain a record of all "runs" made above ten.

- To maintain a record of the "innings" 5 played, I provide another disk 20 and annulus 21, said disk and annulus being revolvably mounted upon the rear side of the disk 1 in the rear of the mouth of the face, and I provide the disk 1 with two openings 22 and 10 23 through which the numerals carried by the disk 20 and the annulus 21 are respectively exposed. The disk 20 and the annulus 21 are also provided with knobs 24 similar to the knobs 19 carried by the other annuli and 15 disks. In order that the large disk 4 may be easily and quickly rotated, the rivet 6 is provided with a button 25, to permit of its rapid rotation to move any of the names of the disk 4 to the opening or slot 7 of the disk 1.
- 20 It is obvious that my improved fan can be readily used as a score card for other games than base ball therefore I do not care to confine myself to the specific construction shown, as various changes in the size, arrangement and minor details of construction 25 may be resorted to without departing from the spirit and scope of the invention.

What I claim and desire to secure by Letters Patent, is:—

- 30 A device of the character described, com-

prising a main disk having a handle secured thereto and provided with a slot and three pairs of openings, the openings of each pair being located close together, a disk rotatably-mounted on the back of the main disk and having a plurality of radially-disposed names thereon to be displayed one at a time through the slot in said main disk, annuli rotatably-mounted on the back of the main disk, one for each of said pairs of openings, each annulus 35 bearing numbers arranged consecutively and adapted to be displayed one at a time through one of the openings of said pairs of openings, consecutively-numbered disks rotatably-mounted within the annuli and lying in the same plane as the annuli, transverse straps secured to the rear faces of the annuli and securing said consecutively-numbered disks within the annuli, a handle-knob carried by each annulus to facilitate operating 40 the same, and a handle-knob carried by each consecutively-numbered disk, substantially as described.

In testimony whereof I affix my signature in the presence of two witnesses.

CHARLES T. FINKBEINER.
